(57) **CLAIM**

The ornamental design for a toy notepaper for a child, as shown and described.

DESCRIPTION

FIG. 1 is a perspective view of the toy notepaper for a child showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 shown in FIG. 6;

FIG. 9 is another perspective view; and,

FIG. 10 is yet another perspective view.

FIGS. 4 through 8 are the left side view, the right side view, the top view, the bottom view, and the cross-sectional view of FIGS. 9 and 10, respectively.

The broken lines showing portions of the stitching and illustrations are included for the purpose of illustrating environmental structure and forms no part of the claimed design.
